An ornamental design for a vehicle taillight, shown and described.

(22) Filed: **Oct. 21, 2008**

DESCRIPTION

(30) **Foreign Application Priority Data**

Jun. 5, 2008 (DE) 40 2008 002 683

The vehicle taillight is styled independently of adjacent vehicle panels. Shading is used to illustrate the curvature of the part and not color. Any functional features of the vehicle taillight are not claimed. Views are orthogonal projections rendered from computer aided design data. The various views are not necessarily to scale in order to better illustrate the design.
